UNITED STATES PATENT OFFICE

2,047,620

COAT AND SLEEVE

Harry C. D'Annunzio, Rochester, N. Y., assignor
to Fashion Park Manufacturing Corporation,
Rochester, N. Y., a corporation of New York

Application September 14, 1935, Serial No. 40,525

2 Claims. (Cl. 2—93)

My invention relates to an improvement in a coat and more particularly in the sleeves of said coat as combined with the coat.

There have been many attempts to construct a coat having sleeves with perfectly free play at the arm holes but none has been developed that permits both free arm movement, free shoulder and back action as the joining of the sleeve at the arm hole of the coat has heretofore always caused a binding or limitation of perfectly free movement in one direction or another and usually in both.

Also, if the arm hole in the body of the coat and the adjoining portion of the sleeve be made unusually large, then the coat and sleeve do not hang or set right and will cause a misfitting coat that will not look right and will not meet commercial requirements as to style and fit.

It is therefore apparent that this is a real problem and that it has not been solved because of the difficulty in securing free arm, shoulder and back action simultaneously with good fit and appearance.

My combined coat and sleeve construction has solved this problem and furnishes not only a coat having a sleeve which permits free arm swinging action but also permits the raising of both arms to the full upright position without raising the shoulders of the coat and the returning of the coat and sleeve to the normal position when lowered to the normal position and at the same time furnishing a fine fitting coat of the finest style and appearance at all times.

Referring to the drawing, Figure 1 is a back plan view of an undersleeve portion of a coat sleeve;

Fig. 2 is a separate element conforming to the upper end of said undersleeve portion;

Fig. 3 is a second separate element similar to Fig. 2;

Fig. 4 shows separate elements 2 and 3 stitched together along the dotted line on the lower edge;

Fig. 5 is a vertical cross section on the line 5—5 of Fig. 4;

Fig. 6 shows my coat with the sleeve in the raised position, both coat and sleeve being broken away for convenience in illustration;

Fig. 7 is the same as Fig. 6, but with the sleeve in the lowered position;

Fig. 8 is similar to Fig. 6 enlarged and with the upper part cut off to show the cross section structure;

Fig. 9 is a front view of Fig. 6.

In the drawing, 10 is the main body of the coat and 11 the sleeve. The undersleeve portion of

the sleeve 11 is 12 and it has an upper end 13. A separate element 14 conforming in shape to the upper end 13 of the undersleeve 12 is adapted to be stitched to a second similar separate element 15 with portion 14' overlying 15' along the dotted line 16 so as to secure said elements 14 and 15 together as shown in Figs. 4 and 5. The upper edge of element 14 is then stitched along the front upper edge of 13, with the portion 14' overlying portion 13'. The element 14 is then turned back over the upper edge of 13 and again stitched to the underside of 13 at 17. The element 15 is then turned back on element 14 along the line of stitching or seam 16 and stitched to the coat 10 at 18 thereby forming an extensible member 19 around substantially the entire armscye. An elastic member 19 is secured at one end to the seam 16 and at the other end to the back or underside of the undersleeve member 12.

It is to be particularly noted that the extensible member formed by the joining together of separate elements 14 and 15 as shown in Figures 4 and 5 actually extends around substantially the entire armscye as indicated at 19 in Figures 6, 7 and 8. Figure 9 shows how this extensible member comes to the very front of the armscye.

In my coat and sleeve construction, I not only have a structure which permits of the ready swinging of the arm and the closing of the opening on the return to the normal position of the arm but also my novel structure permits the full raising of the arm without lifting the shoulders of the coat and displacing same as in all prior structures. Also my combination permits the wearer to use the arms, shoulders and back in a way hitherto impossible without straining or ripping the back of the coat because of the free play to arms, shoulders and back made possible by the same.

There are many variations possible in the particular structure of my device without departing from the spirit and intent of the same and such variations are comprehended within the claims.

I claim:

1. In a coat, a sleeve having the usual undersleeve section, a pair of strip like elements of substantially uniform width each formed with a convex longitudinal edge and a concave longitudinal edge conforming to the upper end of said undersleeve and the first element having its concave edge attached to said undersleeve and thereover substantially along the entire inner edge of the same, said second element being attached along its convex edge to the convex edge of said first

element, the concave edge of said second element being secured to the adjoining arm hole of the coat.

2. In a coat, a sleeve having the usual undersleeve section, a pair of strip like elements of substantially uniform width each formed with a convex longitudinal edge and a concave longitudinal edge conforming to the upper end of said undersleeve and the first element having its concave edge attached to said undersleeve and thereover

substantially along the entire inner edge of the same, said second element being attached along its convex edge to the convex edge of said first element, the concave edge of said second element being secured to the adjoining arm hole of the coat and an elastic element secured at one end to the fastened edges of said two elements and at the other end to the inner side of said undersleeve element.

HARRY C. D'ANNUNZIO. 10
